UNITED STATES PATENT OFFICE

130,835

DESIGN FOR A CLOTHES WASHING MACHINE

Henry W. Altorfer, Peoria, Ill.

Application October 17, 1941, Serial No. 103,792

Term of patent 14 years

To all whom it may concern:

Be it known that I, Henry W. Altorfer, a citizen of the United States and a resident of Peoria, in the county of Peoria and State of Illinois, have invented a new, original, and ornamental Design for a Clothes washing machine, of which the following is a specification, reference being had to the accompanying drawing, forming part thereof.

Fig. 1 is a front corner perspective view of the clothes washing machine, showing my design; and

Fig. 2 is a reduced opposite rear corner perspective view thereof.

I claim:

The ornamental design for a clothes washing machine, as shown.

HENRY W. ALTORFER.
